CLAIM

The ornamental design for an enclosure for electronic equipment, as shown and described.

DESCRIPTION

FIG. 1 is a slightly reduced top front side perspective view of an enclosure for electronic equipment showing our new design;

FIG. 2 is a front elevational view thereof;

FIG. 3 is a left side elevational view thereof, the right side being identical;

FIG. 4 is a top plan view thereof;

FIG. 5 is a bottom plan view thereof; and,

FIG. 6 is a rear elevational view thereof.

The broken lines are shown in the views for illustrative purposes only and form no part of the claimed design.

FIG. 1

FIG. 2**FIG. 6**FIG. 3

FIG. 4

FIG. 5
